UNITED STATES PATENT OFFICE

ROY R. PORTER, OF FORT LEE, NEW JERSEY

LAVATORY

Application filed April 7, 1930. Serial No. 442,416.

This invention relates to improvements in lavatories, and more particularly to an integrally cast lavatory having its back extended upwardly and so formed as to provide an integral medicine cabinet therein which will extend substantially flush with the front of said back.

Other objects will appear as the description proceeds.

10 In the accompanying drawings which form a part of my application,

Figure 1 is a front elevation of my improved lavatory and medicine cabinet showing the door of the cabinet in opened position;

15 Figure 2 is a vertical sectional view through my combined lavatory and medicine cabinet;

Figure 3 is a top plan view of the lavatory 20 and medicine cabinet;

Figure 4 is a side elevation thereof, and

Figure 5 is a sectional view taken on the line 5—5 of Figure 1.

Like characters of reference are used 25 throughout the following specification and the accompanying drawings to designate corresponding parts.

In carrying out my invention, it will be apparent that the combined lavatory and 30 medicine cabinet may be made from any desired material, but it is preferred to make the same from cast iron or from glazed porcelain.

The lavatory 1 is provided with the usual 35 surrounding flange 2, and has its back portion 3 extended upwardly to form a medicine cabinet 4. The side walls 5 of the back 3 are of sufficient depth to provide ample space for the medicine cabinet 4, while the 40 top 6 of the back 3 is formed to provide an integral quarter-round concave reflector 7, and an integral soap holding well 8 and glass holding well 9 at the opposite sides of said reflector. An electric light bulb 10 may be 45 placed in a socket so that the light rays therefrom may be directed by the reflector upon the face of a person standing in front of the lavatory and medicine cabinet to facilitate shaving. A mirror 11 may be suitably supported upon the wall above the

medicine cabinet 4, thereby permitting various selections of style or types of mirrors.

A removable frame 12 will be supported within the medicine cabinet 4, and comprises spaced cross members 13, vertical connecting members 14, and forwardly extending shelf supporting arms 15. Securing bolts 16 will be passed through the back portion 3 and through the spaced cross members 13 to support the frame 12 in position within the medicine cabinet 4. Suitable shelves 17 may be supported upon the arms 15, and may be removed when desired.

Hinges 18 will be carried at the free ends of two of the arms 15, and will in turn support the door 19 to the cabinet 4, and will entirely cover the front of the same. The door 19 is preferably formed of ply-wood with a coating of "viscoloid" of any desired color. An elongated handle 20 is secured to 70 the door 19 and is provided with a plurality of slots or openings 21 to receive and support tooth brushes.

Openings 22 will be formed in the lavatory for the faucets 23, while opening 24 will be 75 provided for the drain or outlet from the lavatory.

Many minor changes in detail of construction may be resorted to without departure from the spirit of the invention.

Having thus described my invention what I claim as new and desire to secure by Letters Patent of the United States is:

An integral casting comprising a lavatory and cabinet for medicines to the rear of said 85 lavatory, the opposite side walls of said lavatory being extended upwardly to form the side walls of said cabinet, said cabinet being entirely located and positioned within the lateral limits of said lavatory and directly 90 above the same.

In testimony whereof I affix my signature.
ROY R. PORTER.
